TELEVISION PICKUP TUBE

Paul K. Weimer, Princeton, N. J., assignor to
 Radio Corporation of America, a corporation of
 Delaware

Application December 20, 1947, Serial No. 792,944

15 Claims. (Cl. 250—153)

1

This invention relates to pickup tubes used for converting photo images into electrical impulses and more especially to tubes in which the cathode ray beam approaches the target at substantially zero velocity but the invention is not limited thereto. The targets in such tubes may be either single or two sided such as in the orthicon and image orthicon described in the patent to Albert Rose, No. 2,407,906, September 17, 1946, and my Patent No. 2,433,941, filed September 16, 1944, Serial Number 554,949, respectively.

In these and other cathode ray pickup tubes the electrons leave the thermionic cathode of the gun at an irregular rate which produces spurious signals called shot "noise." The photo-electrons are also emitted from the photocathode at an irregular or random rate, and produce additional shot noise. It is well known that the electron current emitted by such photocathode has a noise current associated with it given by the formula:

$$(1) \quad I_n = (2efI)^{1/2}$$

where

I_n is the root mean square noise current in amperes

e is the electronic charge

I is the total emitted current in amperes

f is the frequency band width

The maximum signal to noise ratio which may be obtained with a signal current I is given by

$$R_s = \frac{I}{I_n} = \frac{I}{(2efI)^{1/2}} = .79 \times 10^6 I^{1/2}$$

for a band width of 5 megacycles.

The spurious signals produce at the luminescent screen of the receiving tube an effect somewhat resembling flakes of falling snow in the picture which is objectionable. Spurious signals are also superimposed on the video signals by the amplifiers to which pickup tubes are coupled and in order to increase the ratio between signal and noise it has been the practice to greatly increase the signal before it reaches the amplifier by electron multipliers in the tube as in my said application. Since electron multiplication increases the shot noise as well as the signal, maximum signal to total noise ratio is reached, as a practical matter, when the shot noise materially predominates over the amplifier noise. The multiplier gain required for this is approximately 1300. There is, however, a fundamental difficulty in orthicon pickup tubes which prevents the attainment of maximum sig-

2

nal-to-noise ratio at all light levels of the picture. This is due to the inverted polarity of the modulated electron stream entering the multiplier. In both the orthicon and image orthicon the charge image on the target varies in a positive direction with the brightness of the areas of the picture and the low velocity beam scanning the target deposits sufficient electrons to discharge the areas. The fraction of the beam not landing on the target forms a modulated beam which returns toward the cathode ray beam gun and is directed into the multiplier. The current entering the multiplier, and hence the shot noise, is maximum in the dark parts of the picture and minimum in the bright parts which gives a signal-to-noise ratio in the low lights which is poorer than that permitted in the low lights by Equation 1.

There are some types of pickup tubes in which 20 the signal-to-noise ratio at all light levels with electron multiplication is substantially that given by the Equation 1. One example is the dissector tube in which the photoelectrons are scanned over an aperture such as in the patent 25 granted to Farnsworth No. 1,970,036, August 14, 1934. Another is "flying light spot" illumination with photomultiplier cell pick up. Flying spot illumination is well known in the art, an example of which may be found in the book on 30 "Television" by Zworykin and Morton, p. 218, published by John Wiley and Sons, Inc., New York 16, New York.

Such types of prior art tubes do not provide 35 storage of the charge during the entire scanning cycle and this is obviously a great disadvantage. It is an object of this invention to provide a pickup tube that possesses full storage properties and has the maximum signal-to-noise ratio given by Equation 1 at all light levels of the picture.

Another object of the invention is to provide 40 a pickup tube in which the electrons landing on the target and escaping therefrom as scattered electrons are the only ones utilized for producing the useful signal.

Another object of the invention is to provide 45 a pickup tube in which helical motion is imparted to the beam electrons to provide efficient separation of the returning reflected electrons from the returning scattered electrons.

Another object of the invention is to provide 50 a tube in which substantially 100% modulation of the current entering the multiplier can readily be obtained.

Another object of the invention is to provide a

pickup tube having increased signal-to-noise ratio.

Another object of the invention is to provide a pickup tube in which scanned spots on the first dynode of the multiplier are eliminated and do not appear in the transmitted picture.

Another object of the invention is to position the first dynode of the multiplier of a cathode ray beam tube at an antinode of the return beam.

Another object of the invention is to transmit a more uniform signal for black areas of the image.

Other objects of the invention will occur in the following specification, reference being had to the drawing in which:

Figure 1 is a diagrammatic illustration by which the principle of the invention may be explained;

Figure 2 is an imaginary section of the beam illustrating the spiral paths of electrons endwise of Figure 1 at an antinode of the spiral;

Figure 3 is a schematic axial view of a pickup tube embodying the invention;

Figure 4 is an end view of the separator plate and associated parts shown in Figure 3;

Figure 5 is a sectional elevation by which the principles of a second embodiment of the invention may be explained;

Figure 6 is a diagrammatic illustration of spiral paths of the reflected and scattered electrons endwise of Figure 5;

Figure 7 is an imaginary section of the beam of Figure 5 at the separator electrode showing the reflected and scattered electrons of the return beam;

Figure 8 is a graph showing the value of the total return beam and the value of the scattered electron beam at the separator plate;

Figure 9 shows another and preferred embodiment of the invention; and

Figure 10 is an end view of the separator plate and associated parts of Figure 9.

While the invention is not limited to pickup tubes having a magnetic focusing field it will be first described as applied to such a tube.

Referring to the diagrammatic illustration in Figure 1, the gun G projects electrons toward the target T in the magnetic focusing field indicated by field lines F which is produced in a way well known in the art. Part of the electrons of the beam are emitted from the cathode so as to enter the field with a slight inherent component of velocity perpendicular to the focusing field and this, with the longitudinal accelerating field of the anode, or anodes such as the first anode 2 of the gun, produces spiral movement of the electrons, each spiral passing through the center line 3 of the beam. The diameter of the helix traversed by each electron is proportional to its transverse velocity, an end view of the paths traversed can be visualized as in Figure 2, the line 3 of the magnetic field F being the one where some of the electrons enter the field with no transverse velocity. The size of the beam in the figures is of course exaggerated. All of the electrons take the same time for completing a spiral and hence they all cross the line 3 at the same points f, which are called the foci. These foci may also be considered as nodal points or nodes along the beam path. The forward travel of the electrons, that is, the distance between adjacent foci f, of which five are shown, is a function of the accelerating voltage and the strength of the focusing field.

Electrons land on the target T in proportion to the potential of the charge image assumed to be formed thereon and reduce the potential to reference potential assumed to be substantially 5 the potential of the cathode of the gun. The electrons not landing on the target, that is the reflected electrons, return toward the gun along the same spiral paths outwardly traversed and pass through the same foci or nodal points. Some 10 of the electrons landing on the target have sufficient energy to escape and are accelerated back toward the gun. These escaping electrons are 15 called scattered electrons. Since the electrons with transverse velocity leave the gun cathode in various directions, the electrons spiral around many centers spaced around the center line of force 3, such as at 4, 5, 6, and 7. Some of the scattered electrons acquire additional 20 transverse velocities from the positive charges of the target and spiral at greater radii and follow return paths having centers at 8, 9, 10, and 11. There are, of course, a multiplicity of spirals and only a few are given to illustrate the principle. Thus the scattered electrons not 25 acquiring sufficient transverse velocity at the target and the reflected electrons, spiral within the envelope 12. The scattered electrons acquiring sufficient transverse velocity, spiral within envelope 13 outside the envelope 12. Both the 30 reflected electrons, and the scattered electrons, are modulated by the charge image on the target and thus both contain the signal.

Instead of locating the first dynode of the multiplier approximately at anode 2 as in my said application which collects the entire beam of scattered and reflected electrons, I place an apertured first dynode diagrammatically shown at 14 at or near an antinode which is substantially midway between two nodes or nodal points as indicated in Figure 1, the imaginary cross section of the beam being depicted in Figure 2. The scattered electrons outside the envelope 13 then strike the first dynode, as in my said application, while the reflected electrons pass through the aperture in first dynode 14 and are collected by anode 2 and discarded, which anode 2 would not be a dynode as in my application.

In dark areas no electrons land on the target and the scattered electrons are nil. With gray areas the potentials in general are no more than the energy spread of the beam and all of the scattered electrons are intermingled with the reflected electrons. In the bright areas some of the scattered electrons spiral outside of the reflected electrons and strike the first dynode. The total number of scattered electrons are roughly proportional to the number of electrons landing on the target and are proportional to the brightness of the target areas. The signal current, carried by the scattered electrons is therefore of direct, and not reversed, polarity and the modulation can be made substantially 100%.

I prefer not to rely on the inherent transverse 65 velocities of the emitted electrons as just described for separation of the scattered electrons from the reflected electrons as in Figure 1 because (a) part of the scattered electrons are within the reflected beam envelope 12 as is evident from Figure 2, and hence they will pass through the aperture in the first dynode as at 14 and are not utilized and (b) the electrons which land in the gray areas are not scattered beyond the reflected beam envelope 12 and hence 70 cannot be separated from the reflected electrons.

The disadvantage of the first operation will be apparent. The disadvantage of the second is that it amounts to clipping the signal current for gray areas. Greatly reducing the section of the beam eliminates the disadvantageous effects but this is not easily carried out. I therefore prefer to obtain the results by deliberately introducing additional helical motion into the primary beam so that all of the scattered electrons of the return beam are projected from the target so as to be outside the envelope 12 containing the reflected electrons. The increased spiraling may be induced in a number of ways.

One form of cathode ray beam tube for forming a return beam of scattered electrons that do not appreciably intermingle with the returning reflected electrons is shown in Figure 3. In this figure the evacuated envelope 15 of glass or other suitable material contains the gun G, having the usual grid and cathode not shown but shown in my said application to which reference is made for these details. Surrounding the anode 19 of gun G is a block diagram 20 indicating a multiplier M having a plurality of multiplying dynodes, and a collecting electrode shown in detail in my said application. All these elements do not per se constitute my present invention and reference is made to my said application for details of their construction.

The image section of the tube comprises a two-sided target T consisting of a semi-conducting glass 27, or equivalent, as in my said application, closely adjacent to which is the so-called signal screen 28 conductively attached to the electrode cylinder 29 across one end of which the glass target 27 is placed in taut condition. The inside surface of the end of the transparent envelope 15 is coated with a thin semi-transparent conductor on which a light sensitive mosaic is formed, constituting a well known form of photocathode 30. Between the photocathode and the electrode cylinder 29 is placed accelerating cylinder anode 29a. This image section of the tube is constructed as described in my said application.

A field modifying anode cylinder 31 called the "persuader" is positioned in front of the gun G to help direct the secondary electrons from the first multiplying dynode, which in this case is the end of anode 19, into the multiplier unit 29. The anode edge for separating the reflected electrons from the scattered electrons may be edge 32 of the opening of a disc 32a conductively secured to the persuader 31. This aperture may have either a straight edge or a circular edge, the latter being shown (see Figure 4).

A wall coating electrode may be used, as in my said application but for convenience of manufacture I prefer a cylinder anode 33 such as disclosed in my application filed February 7, 1946, Serial Number 646,076, now U. S. Patent 2,452,619, issued November 2, 1948, which performs the same function as a wall coating.

A decelerating anode is positioned between the "wall coating" anode 33 and the glass target 27. This may be an anode ring 34 as in my first mentioned application, but I prefer to use a fine mesh screen 35 across the ring so as to produce a uniform and steep decelerating field in front of the target, which also reduces scanning of the first dynode by the return beam which is desirable in my present invention. The screen 35 and ring 34 may be connected to the anode cylinder 33 or they may be separately supplied with voltage less or more than that of the ring.

An axial magnetic focusing field is produced

in the tube by solenoid 36 energized by direct current. A scanning yoke 37 is placed outside the envelope. This comprises a vertical scanning coil and a horizontal scanning coil (not indicated). These coils are connected to sawtooth generators 38, 39 having the required frequencies and variable voltages to scan the beam across the target. The focusing and scanning coils and the sawtooth generators may be of standard form well known in the art.

An axially adjustable compensating coil 40 may be used to initially align the beam as disclosed in the patent granted to Albert Rose, No. 2,407,905, September 17, 1946, as well as in my said application.

The parts thus far described are the same as, or are known equivalents of, those described in my said application 554,494, now U. S. Patent 2,433,941 issued January 6, 1948, and to produce separation of substantially all of the returning scattered electrons from the returning reflected electrons, I introduce a spiralling velocity component into the beam. As shown in Figures 3 and 4, this is produced by two electrodes 41, 42 very close to the aperture of the beam to which is connected a direct current source of potential that is adjustable so as to control the transverse force applied to the electrons of the beam, such as a bleeder resistance 43. These electrodes are spaced apart equal distances from the beam from the gun which is projected between them. The field produced by these electrodes gives the electrons a transverse component of velocity dependent upon the potential applied thereto. This transverse component produces spiralling of the electrons above the normal spiralling of Figures 1 and 2, as indicated in Figures 5 and 6. Between the separating disc 32a and the anode 33 is placed "lifter" anodes 44, 45 (Figure 4), to deflect the beams so that the return beam B₁ is out of the path of the original beam B. In the axial magnetic field this deflection will be in the plane of the paper in Figure 5. These lifter anodes 44, 45 are known in the art and may be either planar or curved, the latter being shown. The end 46 of the anode 19 may constitute the first dynode 46 of the multiplier.

The operation of the embodiment in Figure 3 may be described as follows:

The various electrodes are given various properly proportioned voltages as will be known to those skilled in the art which particular voltages need not be given. The electrodes 41, 42 cause the electrons of the beam to spiral to a greater extent than indicated in Figure 1. This is illustrated in Figure 5 in which the outgoing beam B is shown in imaginary longitudinal section. The tube is shown broken away to reduce the size of the illustrations. The production of helical movement of the electrons by the electrostatic field of electrodes 41, 42 causes part of the energy of the electrons to be associated with the helical movement and the energy associated with the longitudinal movement thereof is decreased by that amount. The target T may therefore be biased slightly positive with only a few electrons landing in the dark. The polarity of the lifting plates 44, 45, appearing in Figure 3 but not in Figure 5, is such as to bend the beam B down so that electrons spiral through the line 3' instead of 3 as shown in Figure 5. The polarity of the field produced by electrodes 41, 42 is such that electrons of the beam B spiral below a plane perpendicular to the plane of the drawing at the

axis 3 through which, of course, all spirals pass at the focal points f.

When the beam is over a white area, which has a more positive potential, more electrons land, and part of these escape and are scattered. The scattered electrons escape in all directions and spiral as at 47 in Figure 6 all around the focal line 3'. The paths of the reflected and scattered electrons as they are accelerated back toward the gun, are different in Figure 3, from those in Figure 1 as the plates 41, 42 produce a transverse energy component in the beam in one direction, down as shown in Figure 5. When the return beam passes through the field of lifter plates 44, 45 it is moved downwards to the new line 3''. When the return beam reaches the separator disc 32a the scattered electrons B'' pass through the opening therein and the reflected electrons B' land on the disc 32a below the edge 32 as indicated in Figure 7. The scattered electrons then land on the first dynode 46 which is the end of the anode 19 but a separate plate could be used as the first dynode if desired.

The paths followed by the scattered electrons at all points, other than the foci, are not substantially intermingled with the reflected electrons as is evident from Figure 5 in which B' is the beam of reflected electrons and B'' is the beam of scattered electrons. Thus the return beams can be separated at points other than the foci. In Figure 5 they are separated by the disc 32a shown as circular, but not necessarily so, which collects the reflected electrons and passes the scattered electrons above the edge 32. The collector plate 32a is placed at an antinode. All of the reflected electrodes strike the disc 32a below the separation edge 32 and are discarded. The scattered electrons pass through the opening and land on the first dynode 46 located substantially at a node, and bombard secondary electrons therefrom. These bombard additional secondary electrons from the succeeding dynodes in succession in the multiplier M as in my said application 554,494 now U. S. Patent 2,433,941, issued January 6, 1948, and current in the output line L is greatly multiplied.

The lifter plates 44, 45, see Figures 3 and 4, deflect both the outgoing and returning beams down in the plane of the paper in Figure 3 as well known since they are immersed in a magnetic field. The deflection of the outgoing beam deflects the raster on the target, but this is only half the deflection of the return beam. This is usually not objectionable. However, the displacement of the raster on the target may be corrected, if desired, by adjustment of the saw-tooth generator 38 producing the frame scansion.

The advantage my invention has over the standard image orthicon such as disclosed in my first-mentioned application will be apparent from Figure 8. In this figure the total return beam (reflected electrons plus scattered electrons) which enter the multiplier in the prior types of orthicons is given by 54 for black areas and 55 for white areas. In my improvement, the beam entering the multiplier is substantially nil for black areas and is indicated at 56, and that for white areas is indicated at 57. Thus, in my improvement the noise is a minimum, practically zero, in black areas, for the shot noise varies as a current of the beam. The scattered electrons utilized are proportional to the illumination on the picture areas and hence the signal-to-noise ratio may approach the value given by Equation 1. In obtaining this desirable result, storage of the

signal for a full frame time is obtained as this feature is the same as in prior type orthicons.

It is important that the return beam of reflected electrons do not scan the separation disc such as 32a. This is substantially obtained in my improvements because the separation edge is located at an antinode and scanning is also reduced by use of the close meshed screen 35 (Figure 3) closely adjacent the scanned side of the target, for example 0.250 inch. This screen also provides a steep and uniform deceleration field in front of the target. Scanning of the separation plate can also be reduced in various other ways.

In adjusting the improved tube for operation, the various adjustments are made as in the standard image orthicon so as to obtain correct focus of the beam on the target, and with the current directed into the multiplier. In doing this the voltage on the plates 41, 42 is omitted, and the voltage on lifting plates 44, 45 may be adjusted to direct the current into the multiplier. The picture is then noted in a monitor receiving tube. This picture will be negative with maximum output current in the dark as in my application 554,494 now U. S. Patent 2,433,941, issued January 6, 1948. Now voltage is put on plates 41, 42 of the right polarity, and varied. At the correct value the polarity of the picture reverses and changes to positive.

Another embodiment of the improvement is shown in Figure 9. The tube is the same as shown in Figure 3 except (a) the helical motion is produced by adjustment of alignment coil 40, (b) the multiplier units are positioned at one side of an additional anode cylinder 53 in front of the gun, (c) the gun is mounted above the axis of the tube. The remaining parts in this figure, being the same as those in Figure 3, are given the same reference characters as in that figure. Hence, only the newly arranged parts will be described.

The anode cylinder 53 carries at the front end an integral or conductively connected disc 54 having an opening 55 for the outgoing beam (see Figure 10) and an opening 56 therebelow for the scattered electrons. The reflected electrons land on the disc 54. Back of the opening 55 is the first dynode 57 of the multiplier. This may be conveniently made by cutting and bending back the metal in forming the opening 56. The top side of the metal being uncut.

In this modification, adjustment of the alignment coil 40 is such that a sufficient cross field is produced to give the electrons of the beam the desired transverse velocity and in such direction that the returning reflected electrons are below the returning scattered electrons which pass through the opening 56 to bombard first dynode 57. The reflected electrons hit the disc 54 at and below the separation edge 58 and are discarded.

The secondary electrons emitted by the first dynode 57 enter the succeeding multiplier units and multiplication proceeds successively through the multipliers as before referred. The multiplier units may be of any desired type, shown in detail in my said application 554,494 now U. S. Patent 2,433,941 issued January 6, 1948, and in my application filed June 28, 1946, Serial Number 680,002, in which the multiplier surfaces are located at the bottom instead of around the entire circumference. The results obtained by this embodiment are in general the same as in Figure 3, except that I obtain here the additional ad-

vantage that the first dynode is at or near an antinode and thereby out of focus.

The beam may be caused to have the desired helical motion in various other ways than those referred to in the above embodiments, and the invention is not limited to any particular construction. For example, helical motion may be imparted to the outgoing beam by slight misalignment of the gun relative to the axial focusing field.

The invention is not limited to tubes having magnetic focusing fields. Other means for focusing the beam electrons on the target may be used such as electrostatic focusing fields which are, of course, well known in the art.

Various equivalents of the embodiments disclosed may be used without departing from the spirit of the invention.

What I claim as new is:

1. A signal generating apparatus comprising an envelope, means for forming an axial magnetic focusing field within said envelope, a cathode ray beam gun within said envelope having a cathode and positioned to project an electron beam into said field, some of the electrons of said beam having an inherent velocity component transverse to the axis of said field whereby they spiral along said field through common nodal points, a target within said envelope adapted to have substantially the potential of said cathode and positioned in the paths of the electron spirals at a nodal point thereof, and a multiplying dynode positioned in said envelope in the path of electrons landing on the target and scattered therefrom and out of the path of electrons reflected by said target.

2. A signal generating apparatus comprising an envelope, means for forming an axial magnetic focusing field within said envelope, a gun including a cathode and anode electrodes for projecting electrons into said field angularly of the lines of force thereof, whereby the electrons spiral along said focusing field through common nodal points, a target within said envelope adapted to have substantially the potential of said cathode and positioned in the path of the electron spirals at a nodal point thereof, and a multiplying dynode within said envelope positioned in the path of electrons landing on the target and scattered therefrom and out of the path of electrons reflected by said target.

3. A signal generating apparatus comprising an envelope, means for forming an axial magnetic focusing field therein, a target within said envelope adapted to have a charge image thereon and positioned in said field substantially perpendicular thereto, a gun within said envelope including a cathode and anode electrodes for forming and projecting a beam of electrons into said field at an angle to the lines of force thereof whereby the electrons of the beam spiral along said focusing field through common nodal points, electrode means adjacent said target for decelerating the electrons of said beam to substantially zero velocity at the target, said target being at a nodal point of the electron spirals, and a multiplying dynode positioned in the path of electrons landing on the target and scattered therefrom and positioned out of the path of the electrons reflected by said target.

4. A signal generating apparatus comprising an envelope, means for forming an axial magnetic field therein, a target positioned within said envelope in said field substantially perpendicular thereto, a gun in said envelope including a cath-

ode and anode electrodes for forming and projecting a beam of electrons into said field at an angle to the lines of force thereof whereby the electrons spiral along said focusing field through common nodal points, electrode means adjacent said target for decelerating the electrons of said beam to substantially zero velocity at the target, said target being at nodal points of the electron spirals, and a multiplying dynode positioned in

10 the path of electrons landing on the target and scattered therefrom and positioned out of the path of the electrons reflected by said target.

5. A pickup tube comprising an envelope, means for forming a uniform axial magnetic field within said envelope, a target positioned within said envelope in said field substantially perpendicular to the lines thereof, a cathode ray beam gun within said envelope for projecting a beam of electrons along said field towards said target, said gun having a cathode adapted to have substantially the same potential as said target, electric field producing means for causing said beam to enter the axial field at an angle thereto whereby said beam electrons follow spiralling paths 25 passing through common nodal points, said target being positioned at a nodal point of the electron spirals, an electrode having a surface positioned between said gun and said target substantially in the plane of an antinode of the spirals, said electrode having an edge lying between the electron reflected by said target and those landing thereon and scattered therefrom, said surface being in the path of the electrons landing on the target and scattered therefrom and positioned 30 out of the path of the scattered electrons, and a multiplier between said electrode and said gun in the path of scattered electrons passing said edge.

6. A signal generating device comprising an envelope, a target electrode mounted within said envelope, a source of electron emission within said envelope, means for directing said emission as a beam along a normal path to and from said target electrode, an electrode within said envelope for collecting electrons of said beam reflected from said target, and a second electrode within 45 said envelope for collecting beam electrons scattered from the surface of said target.

7. A signal generating device comprising an envelope, a target electrode mounted within said envelope, a source of electron emission within said envelope, means for directing said emission as a beam along a normal path to and from said target electrode, means including an electrode positioned between said electron source and said target electrode for separating the electrons of said beam reflected from said target electrode from said beam electrons scattered from the surface of said target electrode.

8. A signal generating device comprising an envelope, a target electrode mounted within said envelope, a source of electron emission within said envelope, means for directing said electron emission as a beam along a normal path to and from said target electrode, means including an electrode positioned between said electron source and said target electrode for separating the electrons of said beam reflected from said target electrode from said beam electrons scattered from the surface of said target electrode, and an electrode within said envelope for collecting said scattered beam electrons.

9. A signal generating device comprising an envelope, a target electrode mounted within said envelope, a source of electron emission within 75 said envelope, means for directing said electron

emission as a beam along a normal path to and from said target electrode, means including an electrode positioned between said electron source and said target electrode for separating the electrons of said beam reflected from said target electrode from said beam electrons scattered from the surface of said target electrode, said last means including an electrode for collecting said scattered electrons.

10. A signal generating device comprising an envelope, a target electrode mounted within said envelope, a source of electron emission within said envelope, means for directing said electron emission as a beam along a normal path to and from said target electrode, means for establishing on said target electrode a distribution of positive and negative charges with respect to said electron source, means including an electrode positioned between said electron source and said target electrode for separating the electrons of said beam reflected from negatively charged areas of said target surface from said beam electrons scattered from positive areas of said target surface.

11. A signal generating device comprising an envelope, a target electrode mounted within said envelope, a source of electron emission within said envelope, means for directing said electron emission as a beam along a normal path to and from said target electrode, means for establishing on said target electrode a distribution of positive and negative charges with respect to said electron source, means including an electrode positioned between said electron source and said target electrode for separating the electrons of said beam reflected from negatively charged areas of said target surface from said beam electrons scattered from positive areas of said target surface, and an electrode within said envelope for collecting said scattered beam electrons.

12. A signal generating device comprising an envelope, a target electrode mounted within said envelope, a source of electron emission within said envelope, means for directing said electron emission as a beam along a normal path to and from said target electrode, means establishing a magnetic focussing field enclosing said normal beam path between said gun and target, said field having a direction substantially parallel of the normal path of said electron beam, means including an electrode positioned between said electron source and said target electrode for separating the electrons of said beam reflected from said target electrode from said beam electrons given a velocity component transverse to said field direction upon striking said target electrode and scattered therefrom.

13. A signal generating device comprising an envelope, a target electrode mounted within said envelope, a source of electron emission within said envelope, means for directing said electron emission as a beam along a normal path to and from said target electrode, means establishing a magnetic focussing field enclosing said normal beam path between said gun and target and having a direction substantially parallel to the normal path of said electron beam, means for sepa-

rating the electrons of said beam reflected from said target electrode from said beam electrons given a velocity component transverse to said field direction upon striking said target electrode and scattering therefrom, said beam separating means including electrostatic means deflecting said beam transversely to said normal beam path to produce helical motion of the electrons of said beam about said normal electron path and on one side thereof.

14. A signal generating device comprising an envelope, a target electrode mounted within said envelope, a source of electron emission within said envelope, means for directing said electron emission as a beam along a normal path to and from said target electrode, means establishing a magnetic focussing field enclosing said normal beam path between said gun and target and having a direction substantially parallel to the normal path of said electron beam, means for separating the electrons of said beam reflected from said target electrode from said beam electrons upon striking said target electrode and scattering therefrom, said beam separating means including electrostatic means deflecting said beam transversely to said normal beam path to produce helical motion of the electrons of said beam about said normal electron path and on one side thereof, and means positioned on said one side of said beam path to collect the beam electrons reflected from said target electrode.

15. A signal generating device comprising an envelope, a target electrode mounted within said envelope, a source of electron emission within said envelope, means for directing said electron emission as a beam along a normal path to and from said target electrode, means establishing a magnetic focussing field enclosing said normal beam path between said gun and target and having a direction substantially parallel to the normal path of said electron beam, means for separating the electrons of said beam reflected from said target electrode from said beam electrons upon striking said target electrode and scattering therefrom, said beam separating means including electrostatic means deflecting said beam transversely to said normal beam path to produce helical motion of the electrons of said beam about said normal electron path and on one side thereof, and means positioned on said one side of said beam path to collect the beam electrons reflected from said target electrode, and a second collector electrode for collecting the scattered beam electrons returning from said target electrode on the other side of said beam path.

PAUL K. WEIMER.
